UNITED STATES PATENT OFFICE.

WILLIAM M. HOUSE, OF NEW YORK, N. Y.

DESIGN FOR A CLOCK-FRONT.

SPECIFICATION forming part of Design No. 14,886, dated March 18, 1884.

Application filed December 12, 1883. Term of patent 7 years.

To all whom it may concern:

Be it known that I, WILLIAM M. HOUSE, of New York, in the county of New York and State of New York, have invented a certain 5 new and useful Design for Clock-Fronts, of which the following is a specification.

The design consists in the representation of a landscape, including a church or other like building having a steeple, tower, or turret, 10 and a clock-dial in the steeple, tower, or turret.

The accompanying drawing is a face view of a clock-front embodying my design.

A designates a painter's palette, forming the 15 front of a clock-case. On the face of the palette is delineated a landscape in which is prominently represented a building, B, having a steeple, tower, or turret, C. In the steeple, tower, or turret is a clock-dial.

The effect of the design is very unique and 20 pleasing. The clock will have much more the appearance of an ornamental picture than that of an ordinary clock.

What I claim as my design, and desire to secure by Letters Patent, is—

A design for a clock-front, consisting in the representation of a landscape, including a building showing a steeple, tower, or turret, and a clock-dial displayed upon the steeple, 25 tower, or turret of the building, substantially 30 as set forth.

WM. M. HOUSE.
